UNITED STATES PATENT OFFICE.

JOSEPH GREGORY, OF JERSEY CITY, NEW JERSEY.

LAMP-BURNER.

SPECIFICATION forming part of Letters Patent No. 664,742, dated December 25, 1900.

Application filed March 19, 1900. Serial No. 9,284. (No model.)

To all whom it may concern:

Be it known that I, JOSEPH GREGORY, a citizen of the United States, residing at Jersey City, in the county of Hudson and State of New Jersey, have invented a new and useful Lamp-Burner, of which the following is a specification.

My invention is an improved lamp-burner in which the center tube does not extend downward through the oil-chamber, but depends upon air drawn through ports above the oil to supply air to the inside of the flame.

Another feature of my present improvement is a wick-carrier having a vertically-movable partition-plate transversely disposed in the inner wick-tube, between the air-ports thereof.

Another feature of my invention is an improved center tube supplied with air drawn through ports located within the collar of the oil-chamber.

Another feature of my invention is the provision of improved means for preventing the heat from passing from the wick-tube into the oil.

With these and other ends in view my invention consists in the peculiar construction and combination of devices hereinafter fully set forth, and pointed out in the claims.

In the accompanying drawings, Figure 1 is an elevation, partly in section, of a lamp-burner embodying my improvements, the wick-carrier being shown in an elevated position as when a wick is being fitted to the burner. Fig. 2 is a transverse section taken on the line xx of Fig. 1 and showing the wick-raiser lowered. Fig. 3 is a detail view of the wick-carrier as existing when blanked from sheet metal and before being bent and shaped to fit upon the center tube. Fig. 4 is a vertical transverse sectional view of a modified form of my lamp-burner adapted for small glass lamps in which the air-ports are located above the oil-chamber. Fig. 5 is

a detail horizontal sectional view of a modified form of my invention in which the lateral air-ports extending from the center tube are provided with horizontal wings adapted to be fastened to the body of the air-distributer and support the center tube in place. Fig. 6 is a detail view of a modified construction of the lamp-collar.

The wick-carrier 30 is blanked or struck

from sheet metal, as shown in Fig. 3, preferably in one piece, bent on the lines a and b curved to fit the outside of the center tube 6 and adapted to slide vertically thereon. The wick-carrier has its connecting portion b left straight, forming the bridge 10, which unites the two sections c thereof. The wick-carrier 60 is applied to the center tube 6 from the lower end of the latter, the bridge 10 extending transversely across the center tube and adapted to travel in vertical slots 13, with which the center tube is provided, said slots 65 extending to within a suitable distance of the upper end of the center tube and having their lower ends open, as shown in Figs. 1 and 4. The wick-carrier is actuated to raise and lower the wick by a button on the outer end 70 of the shaft 15, which extends through a tube 17, fastened in the upper part of an air-port 7, and on the inner end of said shaft is a pinion 16, which, when the wick-carrier is shipped into position on the center tube, engages a 75 rack-bar 9, with which said wick-carrier is provided. The rack-bar may be struck up from a blank in one piece and is folded upon itself vertically and has its edges laterally extended, thereby forming a partition 8, as 80 shown in Figs. 2 and 4, said partition extending transversely across the center tube 6. The partition 8 and rack-bar 9 being fastened together and the partition 8 fastened to the bridge 10 of the wick-carrier within 85 the center tube, as shown, it is obvious that when a rotary motion is imparted to the shaft and pinion by means of the button vertical motion is imparted to the rack-bar 9, partition 8, and wick-carrier, causing them to move 90 vertically together. The partition serves the double purpose of bracing and guiding the rack-bar and stopping or preventing the air from rushing in from opposite directions through the air-port 7 and of causing the air 95 inducted through said ports to be deflected and caused to pass upward to the flame.

I am aware that it has been heretofore proposed to provide a center tube with a stationary partition located between the air-ports, and this I disclaim. I am also aware that it has been heretofore proposed to employ a wick-carrier having teeth which are normally projected outward into engagement with the wick by riding on the center tube, 100 and this also broadly I disclaim; but owing

to the limited space such a wick-carrier has never heretofore been adapted to a center tube having air-ports, and the same constitutes an important feature of my invention, 5 as hereinafter specifically claimed.

The wick-carrier is limited in its upward movement by the bridge 10 coming in contact with the upper ends of slots 13 and in its downward movement by coming in contact with a stop 14 at the lower end of the center tube, this stop being preferably formed by forcing the metal outward at a suitable point on the lower end of the center tube. By 10 springing the lower end of the center tube inward the wick-carrier may be slipped into position on the center tube over the stop 14, the center tube after the wick-carrier clears said stop immediately springing outward and bringing the stop in the path of the carrier, 15 as will be readily understood. The lower end of the center tube may be closed and slotted to receive the rack-bar and partition in lamp-burners of large size; but this is not necessary in burners of small size. The air- 20 ports 7 are of diamond shape, as shown in dotted lines in Fig. 4 and as indicated in Fig. 1 by the shading, this form of the air-ports adapting my burner to employ the common form of cylindrical wick split upon opposite 25 sides for a suitable distance from one end, such a wick being adapted to open and pass around the ports and resume its cylindrical form below the ports, and thus avoid the necessity of mutilating the wick.

30 In the form of my burner illustrated in Fig. 1 the air-ports are provided with wings 29, turned back from their outer edges to guard the wick and prevent the same from spreading out and closing the air-space 20 between 35 the outer edge of the air-port 7 and the air-distributer 1. In small burners one such air-port may be sufficient, while in very large burners three of such ports may be required, and hence I vary the number of such air-ports 40 and do not restrict myself in this particular. The upper sides of the air-ports are fastened to the under side of a ring 12, which ring is fastened to the air-distributer 1, as shown, whereby the center tube is supported concentrically within the air-distributer. 45

50 In the modified form of my invention shown in Fig. 5 the ring 12 is omitted and wings 31 are made integral with the upper sides of the air-ports 7 and fastened to the body of the lower air-distributer 1 and serve to hold the center tube 6 in position. When the ring 12 is used, it serves to strengthen the burner; but the said ring is not essential to the efficient operation of the burner and may be entirely omitted, as herein indicated.

55 The outer wick-tube 5 is short as compared with the outer wick-tubes of existing lamp-burners of this class, and said tube 5 is provided at its lower end with an outwardly- turned horizontal flange 4, which rests upon the ring 12 and partially closes the annular opening 18, which is between the center tube

and the ring 12. Hence the lower portion of the wick, which extends below the said ring 12, is entirely uncovered to economize in the manufacture of my burner, and to facilitate the wicking I do not use an outer wick-tube below the upper end of the air-ports, nor do I restrict myself to its disuse, as it involves no invention to put in such tube. It will be observed that the upper section 2 of the air-distributer or outer casing of the burner is detachable from the lower section 1 thereof and that the said upper section 2 at its lower edge fits within the upper portion of the lower section 1 and bears upon the flange 4 of the wick-tube, as at 2^a. The air-distributer 2 and the flange 4 may be made integrally and fastened to the lower end of outer wick-tube 5, as usual in center-draft lamps. The chimney-holders and gallery and perforated upper section 2^b of the gallery are supported by the air-distributer 2 and may be detached or secured thereto. By this construction I am enabled to remove the entire outer wick-tube 50 in order to facilitate the fitting of a wick on the burner. The flange 4 at the lower end of the outer wick-tube 5 by being seated on the ring 12 reduces the large wick-space 18 to normal size above the air-ports and prevents the air from passing from the lower air-chamber 20, formed within the lower section of the air-distributer 1, upward into the upper air-chamber 21, which is formed within the upper section 2 of the air-distributer. In the operation of wicking the lamp-burner or attaching the wick thereto it is obvious that when the outer wick-tube is removed the split wick may be readily inserted through the opening 18 around the center tube and that a turn of the button on the wick-raising shaft brings the teeth on the wick-carrier out into engagement with the wick. The outer wick-tube being then replaced, the operation of wicking the lamp is completed. Should it become desirable to secure the flange 4 of the outer wick-tube to the lower side of the upper section of the air-distributer, this may be readily effected in the manufacture of my lamp-burner, as is obvious. In practice I find that the draft is much stronger on the outside of the flame than it is on the inside, and if the space 18 around the wick were left open the air entering the lower air-chamber 20 would be drawn up into the upper air-chamber 21 to the detriment of the supply of air to the inner side of the flame. It was to obviate this difficulty that I have so constructed my improved burner that this space is closed between the upper and lower sections of the air-distributer at the upper sides of the air-ports.

55 In lamp-burners heretofore constructed the wick-tubes extend downward from the burners into the oil-chamber and in direct contact with the oil therein or connected directly with the collar of the oil-chamber, and inasmuch as the wick-tubes become highly heated when the burners are in operation the heat is com-

inunicated from the flame to the oil through the wick-tubes, which are conductors of heat, and hence the temperature of the oil in the oil-chamber is appreciably raised, and this heating of the oil is dangerous and at times results in explosion. In my improved lamp-burner the wick-tubes do not come in contact with the oil, and that portion of the wick which depends below the outer wick-tube is 5 in the air-chamber 20, intermediate of said outer wick-tube and the oil-chamber, where it is kept cool by the currents of air which have gone inward through the perforations in the side of the lower section 1, and hence 10 the oil in the oil-chamber is effectually prevented from becoming heated.

In lamps of large size the air-distributer is detachably fastened to the collar 25 of the oil-chamber. In Fig. 1 this collar is shown 15 as being outturned and extending vertically above the oil-chamber. In the modified form of my invention shown in Fig. 6 this collar 25 is shown as inturned and extending downward within the oil-chamber, and this latter 20 construction of the oil-chamber and collar is preferable, inasmuch as it admits of the burner being correspondingly lowered and brought nearer the oil.

In large lamps requiring considerable quantities of air for the center tube I provide perforations 22 in the oil-chamber around the collar 25, through which perforations the air passes to the center tube through the lower section 1 of the air-distributer and the air-ports 7. I further provide an annulus 24, which is fastened within the oil-chamber below the opening 22 and extends to the lower side of the burner and prevents the oil from passing out through the holes 22 when the 25 oil-chamber is full in the event that the lamp be tilted or inclined when being handled.

In small glass lamps the air-distributer is detachably fastened to a reducer 19, having a threaded nipple 28, which is adapted to be 40 screwed into the collar of the glass bowl, as will be readily understood.

Having thus described my invention, I claim--

1. In a center-draft lamp, the combination 50 with an inner wick-tube having air-ports, of a wick-raiser having a vertically-movable partition extending across the inner wick-tube between the air-ports, substantially as described.

55 2. In a center-draft lamp, the combination of an inner wick-tube, having laterally-extending air-ports, an outer wick-tube, a wick-raiser on the inner wick-tube having a vertically-movable partition extending across the 60 inner wick-tube between the air-ports, and a shaft extending through one of the air-ports and having a pinion engaging a rack-bar with which said vertically-movable partition is provided, substantially as described.

65 3. In a center-draft lamp, the combination of an outer wick-tube, an inner wick-tube having laterally-extending air-ports below

the lower end of the outer wick-tube and provided further with vertical slots on opposite sides, a wick-raiser on said inner wick-tube 70 and having a bridge-piece adapted to work vertically in said slots, a partition-plate attached to said bridge-piece and having a vertical rack-bar, and a shaft extending through one of the air-ports and having a pinion engaging the said rack-bar, substantially as described.

4. In a center-draft-lamp burner, the combination of a lower air-distributer adapted to be attached to the collar of an oil-receptacle, 80 an inner wick-tube supported at its base by said lower air-distributer, said inner wick-tube having air-ports, within said lower air-distributer, an upper air-distributer, on said lower air-distributer and non-communicating 85 therewith, and an outer wick-tube supported by said upper air-distributer, substantially as described.

5. In a center-draft lamp, the combination with an inner wick-tube, having lateral air-ports, of a vertically-movable partition across 90 the path of the air-ports, substantially as described.

6. In a center-draft lamp, the combination with the center tube having lateral air-ports, 95 of a vertically-movable partition located within the center tube across the path of the air-ports, and a rack-bar fastened to the partition and movable therewith, substantially as described.

7. In a center-draft lamp, the combination with the center tube having lateral air-ports, of a wick-carrier sliding on the center tube and having a bridge extending through the center tube and fastened to the wick-carrier, 105 the bridge adapted to move vertically in slots cut in the center tube extending from the bottom upward, a partition within the tube, across the path of the air-ports, a rack-bar fastened to the partition, and the partition 110 fastened to the bridge, a pinion meshed into the rack-bar and having a shaft extending out through the air-port, a button on the end of the shaft whereby a rotary motion is given to the shaft and pinion imparting a vertical 115 motion to the rack-bar, partition, bridge and wick-carrier causing them to travel together, substantially as described.

8. In a center-draft lamp, the combination with an oil-receptacle having a collar to receive a burner, of an inner wick-tube, having one or more air-ports, extending down into the collar, an air-distributer around the air-ports and detachably fastened to the collar, substantially as described.

9. In a center-draft lamp, the combination with an oil-receptacle having a collar to receive a burner, of air-ports to supply air to the inner wick-tube, the air-ports extending below the plane of the collar, a space being 120 formed between the air-ports and collar and communicating with the outer air, substantially as described.

10. In the kind of lamp described, the com-

bination with the center tube, of a wick-carrier formed in two sections, sliding on opposite sides of said tube, and united by a bridge extending through the center tube, said bridge adapted to move vertically in slots cut in opposite sides of the center tube.

11. In a central-draft lamp, the combination with an inner wick-tube supplied with air drawn through an opening in said tube above the oil, of an outer wick-tube terminating at its lower end at a point higher than the said opening in the inner wick-tube whereby the wick-space formed between said wick-tubes terminates at its lower end above said opening in the inner wick-tube, and means to admit air to the wick below said outer wick-tube.

12. In a central-draft lamp, an inner wick-tube, an outer wick-tube disposed around the upper portion thereof, a casing forming an air-space surrounding the lower portion of the inner wick-tube, and extending below the upper plane of the oil-fount, said inner wick-tube having air-ports opening into said air-space at a point below the upper plane of the oil-fount, substantially as described.

13. In a lamp of the class described, the combination with an inner wick-tube, of a detachable outer wick-tube, a wick-space between, said wick-space opening into and passing through an air-chamber before entering the oil-fount.

14. In a central-draft lamp, the combination with an inner wick-tube, supplied with air drawn through an opening in said tube above the oil, of a detachable outer wick-tube disposed around the upper portion of the inner wick-tube and terminating above said opening, said inner wick-tube extending a distance down into the oil-chamber, and means to admit air to the wick below said outer wick-tube, substantially as described.

15. In a lamp of the class described, the combination with an inner wick-tube having lateral air-ports, of a detachable outer wick-tube disposed around the upper portion of the inner wick-tube and terminating above said air-ports, the lower portion of said air-ports extending a distance down into the oil-chamber, and means to admit air to the wick below said outer wick-tube, substantially as described.

16. In a lamp of the class described, the combination of an oil-receptacle having a collar and a series of air-openings adjacent to the collar, a burner seated in said collar, and means, coacting with the burner, to prevent oil from shaking out through the said openings, substantially as described.

17. In a central-draft lamp, the combination with an inner wick-tube supplied with air drawn through an opening in said tube above the oil, of a detachable outer wick-tube, a wick-space between, a perforated air-distributer concentric with the lower portion of inner wick-tube forming an air-chamber, said wick-space opening into said air-chamber.

18. In a lamp of the class described, the combination with an inner and outer wick-tube, of a perforated casing concentric with both said tubes and supporting the same, the perforations in said outer casing extending below the outer wick-tube and said casing detachably connecting the burner to the oil-fount, substantially as described.

19. In a central-draft lamp, the combination with an inner wick-tube having air-ports, of a wick-raiser having a vertically-movable partition extending across the inner wick-tube between the air-ports.

20. The combination with an oil-receptacle having a series of air-openings adjacent to the collar, of a burner having an inner wick-tube provided with air-openings at its base to admit air to the interior thereof, an outer casing, and a detachable outer wick-tube having a base-flange extending to the outer casing, and above the air-inlet openings in said inner wick-tube, substantially as described.

21. In a central-draft-lamp burner, the combination of a fixed, outer, lower casing, adapted for the admission of air to the interior thereof, an inner wick-tube, having air-openings at its base, to admit air to the interior thereof, a detachable upper casing, adapted for the admission of air to the interior thereof, said upper and lower casings not communicating with each other, and an outer wick-tube extending downward to the base of the upper casing, a wick-space being formed between said inner and outer wick-tubes and said wick-space communicating at its lower side with the interior of the lower casing, substantially as described.

22. In a central-draft-lamp burner, the combination of a lower, outer casing, an inner wick-tube having air-inlet openings at its base, to admit air to the interior thereof, an upper casing detachable from the lower casing, and a detachable outer wick-tube having a base-flange forming a division between said upper and lower casings, a wick-space being formed between the inner and outer wick-tubes, said space, at its lower side, communicating with the interior of the lower casing, substantially as described.

23. In a lamp of the class described, the combination with an oil-receptacle having a downturned collar to receive the burner, a series of air-openings to admit air to the space surrounding said collar, and an annulus, below the said collar, of a burner adapted to fit within the said collar and said annulus, said burner having air-inlet openings communicating with the air-space surrounding said collar, substantially as described.

24. In a central-draft lamp, the combination with an inner wick-tube, of a wick-carrier having sections engaging and sliding on opposite sides of said wick-tube, a bridge uniting said sections, and upwardly-extending arms having teeth held out into engagement with the wick by riding on the inner wick-tube, substantially as described.

25. In a central-draft lamp, the combination with an inner wick-tube, of a wick-carrier having wick-engaging teeth held out into engagement with the wick by contact with the wick-tube, said wick-carrier having a bridge extending through the inner wick-tube, substantially as described. 5
26. In a central-draft lamp, an inner wick-tube, a casing forming an air-space surrounding the same, said wick-tube having air-ports opening into said air-space at a point below the upper plane of the oil-fount, substantially as described. 10
27. In a central-draft lamp, an inner wick-tube, an outer wick-tube, a casing forming an air-space surrounding the portion of inner wick-tube below the outer wick-tube and in which the lower portion of the wick is disposed and extending below the upper plane 15 of the oil-fount, said inner wick-tube having air-ports opening into said air-space at a point below the upper plane of the oil-fount, substantially as described. 20
28. In a central-draft lamp, the combination of a casing, an inner wick-tube supported thereby, an outer wick-tube detachably secured to said casing, said outer wick-tube being disposed around the upper portion of the inner wick-tube and said casing forming 25 an air-space surrounding the lower portion of the inner wick-tube, below the outer wick-tube, substantially as described. 30
29. A central-draft-lamp burner having a perforated outer casing forming the connection between said burner and the oil-fount, an inner and outer wick-tube disposed in said casing, the latter admitting air between said outer wick-tube and the oil-fount, to prevent the heating of the latter, substantially as de- 35 scribed. 40
30. In a central-draft lamp, the combination with an inner wick-tube having laterally-extending air-ports at the lower end, a casing forming an air-space around the lower portion 45 of said inner wick-tube, into which air-space said air-ports open, and an oil-fount having openings around the collar thereof to admit air to the lower end of said inner wick-tube, substantially as described. 50
31. In a central-draft burner, the combination of an inner wick-tube having lateral air-ports extending down into an oil-chamber, of a detachable outer wick-tube, a wick-space being formed between said wick-tubes, and 55 an air-distributer detachably connecting said wick-tubes with the oil-chamber, substantially as described. 60
32. In a central-draft burner, the combination with an oil-chamber having a downturned collar, of an inner wick-tube supplied with air drawn through openings above the oil, a detachable outer wick-tube, a wick-space being formed between said wick-tubes, and a perforated air-distributer detachably connecting said wick-tubes with the oil-chamber, 65 substantially as described. 65
33. In a lamp, the combination of an oil-receptacle having an air-space in its upper side communicating with the outer air, and a burner having inner and outer wick-tubes 70 and having a casing surrounding said wick-tubes and forming an air-space, said inner wick-tubes having lateral air-ports opening outwardly into said air-spaces of said casing and said oil-receptacle, substantially as de- 75 scribed. 75
34. In a central-draft burner, the combination with an inner wick-tube having lateral air-ports opening outwardly into an air-space and said air-space opening downwardly into 80 the oil-chamber, of a perforated outer casing forming said air-space, and detachably connecting the burner with the oil-chamber, substantially as described. 80
35. In a central-draft burner, the combination with an inner wick-tube supplied with air drawn through a plurality of openings surrounding the collar of the oil-chamber, of a detachable outer wick-tube, a wick-space being formed between said inner and outer 85 wick-tubes, and a detachable air-distributer surrounding the outer wick-tube and supplying air to the exterior of the flame, substantially as described. 90
36. In a central-draft burner, the combination of an outer perforated casing extending above and below the upper plane of the oil-chamber and detachably connecting said burner with the oil-chamber and forming an air-space within said outer casing, of an inner wick-tube having lateral air-ports opening outwardly into said air-space above and below the upper plane of the oil-chamber, substantially as described. 95
37. In a central-draft lamp, the combination with an oil-chamber having a downturned collar and openings to admit air to the space surrounding said downturned collar, of a burner having a casing, the lower portion of which forms an air-chamber communicating 100 with the outer air, an inner wick-tube having air-ports communicating with said air-chamber and leading to the center of said inner wick-tube, and a detachable outer wick-tube having a base-flange extending to and supported in said casing, at a point between the upper and lower sides thereof, an air-space being formed in said casing, around said outer wick-tube, above said flange, substantially as described. 105
38. In a central-draft lamp, the combination of an inner wick-tube, a detachable outer wick-tube and an oil-fount having openings above the oil-level, to admit air to the inner wick-tube, substantially as described. 110
- In testimony that I claim the foregoing as my own I have hereto affixed my signature in the presence of two witnesses. 115
